UNITED STATES PATENT OFFICE.

JOHN J. CRUME, OF AMARILLO, TEXAS.

HOLDING-CLIP.

1,196,087.

Specification of Letters Patent. Patented Aug. 29, 1916.

Application filed December 1, 1913. Serial No. 804,067.

To all whom it may concern:

Be it known that I, JOHN J. CRUME, a citizen of the United States, residing at Amarillo, in the county of Potter and State 5 of Texas, have invented a new and useful Holding-Clip, of which the following is a specification.

This invention relates to improvements in holding clips.

10 An object of the present invention is to provide a holding clip which will combine a high degree of resiliency with increased strength.

15 A further object is to provide a clip in which the resiliency is magnified by providing a return arm secured to one extremity of the holding portion so that there will be little danger or likelihood of the clip breaking at its point of attachment.

20 A further object is to provide an improved form of clip wherein there will be little or no tendency for the clip to break or become fractured at its point of support as is one of the serious objections to the form of clip 25 now in common use.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferable form of my invention is illustrated, in which:—

40 Figure 1 is a sectional view of my improved clip and illustrating the manner in which it is secured in place. Fig. 2 is a perspective view of the clip as it appears detached.

45 Referring to the drawings in which similar reference numerals designate corresponding parts throughout the several views, 3 is a plate which may be of metal, or other rigid substance and upon the outer side of 50 which is secured the facing or covering 4. For purpose of illustration, the plate 3 may be considered as the external wall of a spectacle case and the covering 4 the cover which usually extends thereover in order that a 55 neat and finished appearance will be given to the case. In this connection however, it is to

be noted that the clip herein disclosed may be used with equal facility upon other articles.

The plate 3 is provided with the oblique opening 5 extending therethrough and through which extends the securing end 6 of the clip. The securing or supporting end 6 of the clip includes the offset portions 7 and 8 which are connected by an angularly disposed intermediate portion 9. The oblique or intermediate portion 9 extends through the oblique opening 5 in the plate and is crimped or bent into contact with the side walls thereof so as to be rigidly secured thereto. The portion 8 constitutes what is 70 termed the rear arm, the extremity 10 of which is connected to or formed integral with a loop 11. The opposite extremity of the loop 11 carries the front arm 12 and which arm forms an attaching member or 75 portion of the clip. The attaching arm 12 is convex or arcuated in general outline and is provided with the outwardly bent ends 13, one of which is formed integral with the loop 11 and the remote end being adapted 80 to receive the cloth or allied material thereunder to which the clip is to temporarily engage. Thus the general contour of the attaching arm is similar to a cycloidal curve 85 in which the cusps are slightly rounded or modified.

The plate 3 and covering 4 are provided with the aligned apertures 14 extending therethrough and through which the loop 11 extends. Attention is called to the fact that the apertures are of sufficient size to accommodate the loop 11 therethrough and to not interfere with the free play thereof. Also mention is made of the fact that the rear arm 8 does not contact throughout its entirety with the plate 3 so that the resiliency of the clip will be due to the summation of the resiliency of the front and rear arms. The clip therefore can be made of material of some little strength and at the same time 100 the desired amount of resiliency will be maintained. Also the clip will not bend or flex at one special point as do the clips now in general use, which renders the clips liable to break at the point at greatest pressure 105 which is at the point of securing the same to the article upon which it is to be used. It is to be noted in this connection that although the arms have been termed front and rear, the terms are merely relative and indicate 110 that there are two arms rather than the respective positions of the same.

Having thus fully described my invention, what I claim is:—

As an article of manufacture, a clip for the purpose indicated comprising front and rear clamping and attaching arms connected by a loop, the front or clamping arm being of arcuate form to provide spaced bearing points and the rear or attaching arm being longer than the front arm and terminating 10 in a forwardly offset and reduced bearing

extremity arranged substantially in the plane of the bearing points of the front or clamping arm.

In testimony that I claim the foregoing as my own, I have hereto affixed my signature 15 in the presence of two witnesses.

JOHN J. CRUME.
